ROTARY INTERNAL COMBUSTION ENGINE

William H. Card, Los Angeles, Calif., assignor of
one-half to Harry M. Swensen, Los Angeles,
Calif.

Application June 12, 1934, Serial No. 730,208

2 Claims. (Cl. 123—43)

My said invention relates to rotary internal combustion engines, in which a stationary cylindrical shaft, supported at its ends (preferably by the walls of a housing) is provided with an eccentric portion. A rotor, comprising a tubular shaft, having cylinder blocks clamped or otherwise rigidly secured to it, is journalled on non-eccentric portions of said stationary shaft. A plurality of cylinders are formed in said blocks. 5 Connecting rods of pistons within, and adapted to reciprocate with relation to said cylinders, are floatingly pivoted, each to one bifurcated end of a respective rocker-arm, the other end of which rocker-arm is fixedly pivoted, with relation to the cylinder block, said rocker-arm at an intermediate point being also pivoted to a strap which strap is journalled on the above-mentioned eccentric portion of said stationary shaft.

Relative reciprocatory motion between cylinders and their respective pistons, induced by conventional means well known in the art of internal combustion engines, is utilized by means of said eccentric and the linkage connections above briefly described to cause the whole rotor, comprising tubular shaft, cylinder-blocks, pistons, cam and valve assemblies and parts of an ignition system to revolve around said stationary shaft, thus to function as a power rotor.

An important feature of said invention is that 30 which provides an oil reservoir in the bottom of the housing, into which cam shafts, outer ends of valve stems, and other parts of the revolving mechanism dip at each revolution, thus atomizing the oil and spraying it, not only into the 35 interior of the cylinders for conventional cooling purposes, but over and through every part of the working mechanism.

It may aid to a quick perception of the operation of the device to preliminarily explain that 40 pistons in each associated pair of cylinders reciprocate synchronously in unison, and to provide, for instance, for four-cycle operation, while one of an associated pair of pistons moves in a power stroke, the piston in its companion cylinder, moving synchronously and in unison in the same 45 direction, is drawing in a charge of fuel mixture; while of the remaining pair of cylinders one is moving to expel the exhaust gases, while its companion is moving synchronously and in unison in the same direction to compress its fuel charge.

A broad general object of the invention is to provide a simple, compact, and efficient motor of comparatively light weight, and of great power in 50 comparison with its weight, wherein each of the

parts is easily accessible for replacement and repair.

Another important object is the saving of construction cost by the elimination of unnecessary parts and material and the rejection also of 5 forms of mechanism requiring costly machining operations.

Still another object is the provision of a cooling and lubricating system, which, while highly efficient, permits the elimination of expensive 10 conventional equipment for such purposes, such as the radiator and water and oil pumps.

Efficiency and economy of operation are still other objects which are provided for, among other things by the assemblage which permits the 15 use of roller bearings throughout, otherwise avoiding, particularly in the case of the power shaft, the comparatively great friction of Babbitt metal bearings,—the provision for maintaining such bearings in a constant bath of sprayed oil 20 adding infinitely to their most efficient operation and long life. The comparatively light weight above mentioned is involved in a most important object of devising a construction and mode of operation which does not require the use of a 25 heavy fly wheel, the cylinders and their associated parts comprising the rotor adding to their usual function that of maintaining momentum; and the compactness of the assemblage, which allows short connecting rods and rocker arms 30 eliminating much weight and saving metal, while not sacrificing bore of the cylinders or stroke of the pistons.

Other objects and corresponding advantages 35 such as the important one of compactness resulting in economy of space of installation, accessibility for inspection of all working parts, the fact that the motor is designed so that due to the eccentric action the pistons are allowed to travel slower on the power and intake cycles than on 40 those of the exhaust and compression, thus promoting the efficiency of operation heretofore mentioned, and the fact that the centrifugal motion of the rotor is utilized to cool and return the sprayed oil to the reservoir for continued use, 45 —all will be obvious to those of skill in this art from the following detailed description.

In the drawings, Fig. 1 is a longitudinal section through the motor, certain parts being broken away;

Fig. 2 is a cross section as seen on plane 2—2 of Fig. 1;

Fig. 3 is a top plan view, the housing being shown in section as indicated by line 3—3 on Fig. 2;

Figs. 4 and 5 are detail sections as seen on correspondingly numbered planes of Fig. 1; and

Fig. 6 is a wiring diagram.

Referring with more particularity to the drawings, the motor comprises a pair of cylinder blocks 8 and 9 clamped together about a tubular main shaft 10 and further secured thereon by keys 11. Main shaft 10 is rotatably supported in a cylindrical housing 12, by means of bearings 13 and 14, which are shown as bronze bushings, but anti-friction bearings of ball or roller type may of course be used. The housing 12 is formed of upper and lower halves 15 and 16, provided with suitable flanges and secured together with bolts. The lower half serves as an oil reservoir and may be provided with feet 17 to form a convenient method of supporting the motor. The upper half 15 has a large opening 18 closed by a cover 19, which may be removed to allow easy inspection of the working parts. Cover 19 has a screened opening 20 on one side while on the opposite side is an oil pan 21 from which an oil return duct 22 leads to the housing.

Co-axially of main shaft 10 is a stationary shaft 24 supported on anti-friction bearings 25 and 26 and provided with a flange 27 adapted to be secured to the outside of the housing as by cap screws 28. Between bearings 25 and 26 an enlarged eccentric portion 29 is formed on the stationary shaft. Shaft 24 also has a bore 30 closed at its inner end provided with ports 31 and 32 and connected to a carburetor 33 at its outer end. A bevel gear 34 is attached to the inner end of shaft 24 and is held stationary thereby.

Referring again to main shaft 10: this is made in two separate sections (see Fig. 1) one of which, indicated by 10a, extends between eccentric 29 and flange 27 on shaft 24, and the other 10b extends from eccentric 29 on through bearing 14. This section carries the ignition timing mechanism indicated by 35, to be more fully described later, and a fly wheel 36, preferably having the spokes 37 formed as fan blades.

Cylinder blocks 8 and 9, have abutting faces 40 and 41 which meet on a diameter of shaft 10, and flanges 42 with inclined surfaces 43 parallel with face 40. Clamp blocks 44 having bevelled lips 45 to engage surfaces 43 are provided, a long bolt 46 tapped into shaft 10 serves to secure the clamp block in place. The arrangement is such that lips 45 engage surfaces 43 and as the clamp block is drawn inwardly by bolt 46, the cylinder blocks are wedged tightly together. Suitable dowel pins may of course be provided to insure proper positioning of the blocks.

As cylinder blocks 8 and 9 together with their pistons, valves, and associated mechanism are identical, only one will be described, such description applying equally well to the other. Cylinder block 9 has a pair of parallel bores 47 within each of which a trunk piston 48 is arranged to reciprocate. Pistons 48 are of a type commonly used in internal combustion motors and have piston rings 49 and wrist pins 50. Mounted on wrist pins 50 are short connecting rods 51 the outer ends of which are pivotally connected by means of pins 52 to a forked rocker arm 53 (see Fig. 3). The opposite end of rocker arm 53 is oscillatably supported on pin 54 which is supported by clamp blocks 44. Between pins 52 and 54 is a crank pin 55 to which is attached an eccentric strap 56. This eccentric strap encompasses a large ball bearing 57, and is held in place thereon by having the strap shrunk on. Ball bearing 57 is also pressed on eccentric 29. (See Fig. 5.) The con-

struction is such that as the pistons reciprocate within their bores, the entire cylinder block assembly is caused to revolve about stationary shaft 24.

A detachable head 60 closing the upper end of bores 47 is secured to block 9 by bolts 61, the usual gasket being employed to prevent leakage. A combustion space 62 is formed over bore 47, and inlet and exhaust ports 63 and 64 respectively communicate therewith. Communication between ports 63 and 64 and combustion space 62, is controlled by poppet valves 65 and 66 which are normally held in closed position on their seats by compression springs 67.

Ports 68 are formed in the cylinder block and connect inlet ports 63 with openings 69 in shaft 10. Packing blocks 70 and 71 are fastened on shaft 24 between bearings 25, 26 and eccentric 29. Each has an external annular groove 72 which connects with ports 31 or 32, as the case may be of shaft 24 by radial port 73. Thus intake port 63 is in continuous communication with carburetor 33 through ports 68, 69, annular groove 72, port 73, ports 31 or 32, and bore 30 in shaft 24.

Similarly passageways 74 connect exhaust ports 64 with the inside of shaft 10 through openings 75 formed in the walls thereof. Orifices 76 in flange 27 permit the exhaust gases from the left hand end of the motor to escape, while those from the right hand end escape directly from the bore of shaft 10.

A cam shaft 78 is supported in bearings 79 mounted on blocks 44 and is arranged to be driven by gearing later described. Each cam shaft has cams 80 adapted to open valves 65, 66 by unseating them against the pressure of springs 67. A spark plug 81 is placed in each combustion space to ignite the mixture. The cycle of events and the valve action is the same as in the conventional type of four cycle internal combustion motor.

A bevel gear 82 is attached to cam shaft 78 and meshes with a pinion 83 attached to the end of a cross shaft 84. This cross shaft is supported in bearings 85 and 86, and carries an intermediate gear 87 engaging stationary pinion 34. The arrangement is such that as the cylinder assembly revolves about stationary shaft 24, the cam shaft 78 will rotate in its bearings at one half the number of revolutions.

The ignition system will now be described: Referring to Figs. 4 and 6, a conventional type of low tension circuit breaker is illustrated. A plate of insulating material 90 encompasses shaft 10 and is held in place against the outer face of bearing 14 by cap screws 91. A breaker arm 92, also of insulating material is pivotally attached to plate 90 by a stud 93 and carries a roller 94 adapted to be engaged by projections 95 on shaft 10. The opposite end of the breaker arm carries a contact point 96 which may be grounded to the engine frame by lead 97. Contact point 96 normally closes a circuit through a second contact point 98 carried on plate 90 and adjustable with relation to point 96. A tension spring 99 serves to keep the points normally in contact.

A distributor 100 is mounted on cam shaft 78, and is formed of a cylinder of insulating material 101, encircled near either end by metal contact strips 102, 103. Between strips 102 and 103 are segmental strips 104 and 105. Segment 104 is connected to strip 102 while segment 105 is connected to strip 103. Brushes 106 and 107

are suitably supported in an arm 108 of insulating material and are in sliding contact with strips 102 and 103 respectively. A thin metal strip 109 connects each brush with a spark plug 81.

On the inside of the upper half of the housing 15 near its center is an arcuate piece of insulating material 111 carrying a conductor strip 112 (see Figs. 2 and 3). A similar piece of insulating material 113 of greater width but without the conductor strip extends along the inner periphery of the lower half of the housing (see Figs. 1 and 2). The construction is such that as the cylinder block assembly revolves, the segmental strips 104 and 105 on the distributor will pass very close to the conductor strip 112 and due to the rotation of cam shaft 78 and distributor 100 segment 104 and segment 105 will alternately be exposed to the conductor 112.

20 The ignition system in general follows conventional lines, as will be evident from an inspection of Fig. 6. The breaker mechanism, previously described, is connected between one side of the primary 114 of an induction coil and ground. 25 The other side of the primary is connected to one pole of a battery 115 or other source of current, a switch 116 being interposed whereby the current flow may be stopped when desired. The other pole of the battery is grounded. The secondary of the coil 117 also has one side grounded through lead 118, the other side being connected through a lead 119 to conductor strip 112.

As shaft 10 revolves, projection 95 rides under roller 94 swinging arm 92 about its supporting pivot and breaking the contact between points 96 and 97. This interrupts the flow of current through the primary 114 (assuming of course that switch 116 is closed) and induces a high tension current in secondary 117, all in a manner well understood. At the time the primary circuit is broken one of the distributors 100 will be at some point intermediate the length of conductor strip 112, and either segment 104 or 105 will be adjacent to it. Thus the high tension current will flow from secondary 117, through lead 119, conductor 112, segment 104, for example, and its connected strip 102, brush 106 and lead 109 to spark plug 81. Thence across the spark gap to ground in the cylinder block and engine frame. The insulating plate 113 is to preclude the possibility of the high tension current straying from the outer end of the spark plug to housing instead of jumping the gap as desired.

The housing is filled with oil to about the level indicated by numeral 120, and as the motor turns over it is pulsed and distributed to all moving parts in the form of a fine spray or mist. It collects on the cover 19 and runs back into pan 21, from where it is returned to the housing through tube 22. The fan blades 37 in the fly wheel circulate air about the housing, which serves to cool the motor.

While I have thus illustrated and described a specific embodiment of my invention in which there are four cylinders and four-cycle operation, and in which associated pairs of cylinders are arranged so that their axes are parallel, it will be quite obvious to those of skill in this art that more or less than four cylinders may be employed and the axial arrangement, and linkage connections may be changed without departing from the spirit of my invention.

What I claim and desire to secure by Letters Patent is:

1. In a four-cycle rotary internal combustion engine, the combination of a stationary shaft carrying an eccentric, two rotatable hollow shaft members, each enclosing and journaled concentric with portions of said stationary shaft, two pairs of cylinders rigidly secured in spaced relation to and in parallel axial alignment with each other, one pair of said cylinders on each of said rotatable hollow shaft members, one pair of each of said cylinders being on diametrically opposite sides of its respective rotatable hollow shaft member, pistons in each of said cylinders, a strap journaled on said eccentric, said strap having oppositely disposed radial arms, linkage pivotally connecting each of said pistons to said strap and to a point fixed with relation to said cylinders, and means comprising fuel feeding, ignition, and exhaust mechanism to cause relative reciprocatory motion of said pistons and cylinders. 40

2. In a rotary internal combustion motor, the combination of a fixed support, two rotatable hollow shaft members carried in axial alignment by said support, a pair of cylinders rigidly secured in spaced relation and in parallel axial alignment with each other on each of said rotatable shaft members, all of said cylinders having their axial centers in the same plane, one pair each of said cylinders being secured on a side of said rotatable hollow shaft members diametrically opposite that of the other pair of said cylinders and one pair of said cylinders having their bores opening in a direction opposite the other pair of said cylinders. 50

WILLIAM H. CARD.
